Nelson W. Howard

UNITED STATES PATENT OFFICE.

WALTER W. SLACK, OF SPRINGFIELD, VERMONT, ASSIGNOR TO FITZ-EMPIRE DOUBLE PIVOT LAST COMPANY, OF AUBURN, MAINE, A CORPORATION OF MAINE.

HINGE LAST.

Application filed October 24, 1922. Serial No. 596,657.

This invention relates to collapsible lasts, and is disclosed in its application to an impositive lock last, that is, a last which can be collapsed by pressure alone but which 5 offers to collapse a definite and increasing resistance over a short distance from the extended position. Lasts of this type require some sort of resilient structure to furnish the required resistance. Several practical 10 solutions of the problem have been provided by the inventions of H. W. Lucas, (application Serial No. 514,722, filed Nov. 12, 1921), and G. C. Thomas (application Serial No. 516,194, filed Nov. 18, 1921), 15 which provide a resilient hinge, anchor, or abutment pin arranged to receive a bending stress as the collapsing movement begins, thus offering a resilient and increasing resistance to such movement. The present invention 20 has for an important object still further to simplify and improve constructions embodying this principle.

Accordingly, in accordance with an important feature of the invention, the illustrated collapsible last has a pin for the purpose described, supported by terminal enlarged portions shown as bushings at its ends in a hole of a diameter substantially larger than its unenlarged middle portion, 30 the oversize hole providing space for it to bend when deformed by the stresses incidental to collapse.

These and other features of the invention, including certain details of construction and 35 combinations of parts will be best understood from the following description of a preferred embodiment selected for purposes of illustration and shown in the accompanying drawings, in which

40 Fig. 1 is a side elevation of a last embodying the invention, partly broken away to show the mechanism.

Fig. 2 shows the last of Fig. 1 collapsed.

45 Fig. 3 is a section on the line 3—3 of Fig. 1.

The last shown consists of a heel part 10, a forepart 12 and a bonding member 14 linking them together. The heel part and forepart are separated by a cut of such shape 50 as to permit them to turn relatively to each other. In the last illustrated the cut comprises a V-shaped opening 16 at the top of the last, a circular knuckle 18 on one part bearing in the other, and a straight

portion 20 extending from the knuckle 55 to the bottom of the last. The link 14 is anchored in the last parts by pins 22, 24, passing transversely through the last parts. These pins are herein shown as cylindrical 60 throughout and are mounted in holes 26 considerably larger than themselves, and are supported by bushings 28 at their ends which tightly fill the holes 26. The bushings may be tapered to facilitate driving 65 them in when the last is assembled to overcome the stress imposed on the pins by the link 14 in the assembling of the last in order to hold the last parts firmly together in normal position.

The line 30 joining the centers of the pins 70 22, 24 passes below the center 32 of the knuckle 18, when the last is in extended position, as shown in Fig. 1. As the heel parts rises in the collapsing movement, this line rises toward the center 32, and may 75 pass it. As it approaches the center 32 the pins bend still further from the initial contour imposed on them in assembling the last, as shown in Fig. 3 in dotted lines, 80 since the effective length of the link 14 is 80 substantially less than the sum of the distances from the center 32 to its (effective) ends, during the first part of the collapsing movement.

The large holes 26 provide spaces in the 85 last into which the pins have room to bend. The link 14 may be made wide as shown, in order to support the last parts against twisting stresses.

The resiliency of the pins provides an 90 initial definite and increasing resistance to collapse, and thus the structure illustrated constitutes an impositive lock for the last. If the line 30 passes above the center 32 in collapse the last will be impositively 95 locked in collapsed position also.

One of the pins may fully fill its hole, as in ordinary last construction, leaving the other to perform all the functions of the impositive lock, if desired. The distortion 100 of the other pin is then measured by the distance between the two arcs 38, 40, one of which is struck from the center of the ordinary pin for example the heel part anchor pin and passes through the center 22 105 and the other of which is struck from the pivotal center 32 on which the last parts swing and passes through the center 22 also.

In order to keep the parts tight at all times the angle 16 of the cut in the last should not be much greater than the angle 42—32—22 between the intersections of the arcs 38, 40, measured at the pivotal center 32.

Having described my invention, what I claim as new and desire to secure by Letters Patent of the United States is:

- 10 1. In a last, a heel part, and a forepart arranged for relative collapsing movement, a pin arranged during collapse to receive stress from one last part at its ends and from the other last part at its central portion, the 15 pin having bushings at its ends supporting its central portion out of contact with the last parts.
- 20 2. In a last, a hinge pin of substantially uniform cross-section, the last having a hole substantially larger than the pin with bushings supporting the ends of the pin in the hole, and a member arranged to deform the pin transversely at its middle part to a substantial degree during the collapse of the 25 last.
- 30 3. In a last, a heel part and a forepart, arranged for relative collapsing movement, a link connecting them, a pin mounted in each last part, said link being mounted at its ends on said pins respectively and said link and pins being constructed and arranged to hold the last parts firmly together, and one of said last parts having a hole of greater diameter than that of the pin mounted 35 therein, the pin being bushed at its ends to support it in said hole.
- 40 4. In a last, a heel part and a forepart, arranged for relative collapsing movement, a link connecting them, a pin mounted in each last part, said link being mounted at its ends on said pins respectively and said link and pins being constructed and arranged to hold the last parts firmly together, and one of said last parts having a hole of greater 45 diameter than that of the pin mounted therein, the pin being bushed at its ends to support it in said hole, said link and last

parts being constructed and arranged to deform the pin by a pull on the link as the last collapses.

50 5. In a last, a forepart, a heel part arranged to turn relatively about a center to collapse the last, a link joining them with its effective length lying below said center when the last is extended, one of said last parts having a hole, and a pin mounted in said hole and passing through an end of said link, said pin being substantially smaller than the hole, and having bushings at its ends to support it in the hole.

60 6. A last comprising a heel part and a forepart arranged to rotate relatively to effect collapse of the last, a link joining the last parts, the effective length of the link being less than the sum of the distances of 65 its ends from the center of rotation, and said effective length lying below the said center when the last is extended, a resilient pin connecting one end of the link to its last part, arranged to bend under the stress 70 of collapse, the said last part having a hole in which the pin is mounted, said hole being substantially larger than the pin to provide room for bending, and bushings in the hole supporting the ends of the pin.

75 7. A hinged last comprising a forepart and a heel part capable of movement between an extended position and a collapsed position, a bonding member connecting them constructed and arranged to permit them to move from one of said positions to the other, and a resiliently distortable pin arranged resiliently to resist such movement and to cooperate with the bonding member to hold the last in extended or collapsed position, 80 said pin having a cylindrical middle portion and enlarged end portions and the last having a hole in which said pin is mounted which hole is substantially larger than the middle portion of the pin to permit distortion 85 of the pin at the middle portion.

In testimony whereof I have signed my name to this specification.

WALTER W. SLACK.
